UNITED STATES PATENT OFFICE

RUDOLPH TRAHAN, OF RUMSTICK POINT, RHODE ISLAND

VALVE-GRINDING DEVICE

Application filed April 11, 1930. Serial No. 443,328.

This invention relates to a valve grinding device, and has for its object to facilitate the grinding of valves, the stems of which have enlargements at both ends to prevent the 5 valve stem from being drawn axially through its guide.

A further object of this invention is to provide means which will hold the guide, which must necessarily be made in separable 10 sections, in assembled relation, and at the same time serve the additional purpose of raising the valve from its seat when the grinding pressure upon it is released.

With these and other objects and ad- 15 vantageous features in view, the invention consists of a novel arrangement of parts more fully disclosed in the detailed description following, in conjunction with the accompanying drawings, and more particularly set 20 forth in the appended claims.

In the drawings:

Fig. 1 is a fragmental sectional view of an engine showing a valve in substantially its relation to its seat with the valve grinding 25 device of this invention in working position;

Fig. 2 is a sectional view of the valve;

Fig. 3 is a perspective view of the sections of the guide member;

Fig. 4 is a side elevation of the spring; and

Fig. 5 is a side elevation of the device in 30 assembled relation about the valve and ready for insertion therein through the valve seat opening.

In certain automobiles, particularly the 35 model A Ford, the valves are so constructed as to make grinding thereof difficult, even for the experienced mechanic, by reason of an integral enlargement at the lower portion of the valve stem preventing axial re- 40 moval, the construction being such that the valve guide itself must be removed from the bore adjacent the valve port in order to permit the removal of the valve as is necessary for grinding purposes during which this 45 guide must be frequently inserted and re- moved to accomplish the desired result. This guide which must be handled is made in sections and permit of their being dropped, increasing the labor and annoyance to the 50 mechanic working upon the same; and in

order to facilitate the grinding of a valve of this character, I have provided a sectional body member which may be assembled about the valve stem after its usual guide has been removed from the engine block, which guide 55 may be inserted through the valve seat opening into the valvestem bore of the engine block from the upper end, and I have provided a coil spring to hold the sections in assembled relation, and at the same time serve to yield- 60 ingly lift the valve head from its seat upon the release of grinding pressure; and the following is a detailed description of the present embodiment of this invention illustrating the preferred means by which these ad- 65 vantageous results may be accomplished.

With reference to the drawings, 10 designates a cylinder block, shown fragmentally in Figure 1, which has a ground valve seat 11 for receiving the ground portion 12 of the valve head 13 to control the entrance from either the intake or exhaust port 14 to the combustion chamber above the valve head, not illustrated.

The valve, which is typical of the model A 75 Ford, has a valve stem 15 extending from the head 13 with an enlarged lower end 16 tapered as shown in the drawing, which prevents the valve from being drawn axially through its guide, not shown, which is inserted upwardly in the direction of the arrow 17 into the lower end of the bore 18 of the block 10. In order that a valve of this character such as used in the model A Ford motor may be ground, the usual valve guide, 85 not shown, must be removed downwardly in a direction opposite to the arrow 17 from the bore 18, after which the valve may be removed and the valve grinding device assem- 90 bled about the valve stem 15, the same con- 95 sisting of a body portion formed in sections, preferably in halves, 19, grooved as at 20 to form when assembled, a bore fitting the valve stem 15, but slidable thereon, for guid- ing the same in its movement.

The body is cylindrical on its outer surface to fit the cylindrical bore 18 into which the lower portion 21 of this body may be inserted to rest upon the shoulder 22 formed by the flange 23 extending from its outer surface.

The upper portion 24 of the body is also cylindrical and receives a tightly coiled portion 25 of the helical spring 26 which holds the halves or sections of the body in assembled relation about the valve stem 15, and as this spring 26 normally assumes an axially extended helical formation, it engages beneath the valve head 13 and resiliently lifts the same from its seat 11, which is of convenience in grinding the valve in order to better distribute the abrasive material used.

After grinding is accomplished by suitable movement between the valve head 43 and its seat, the body 19 of the device may be lifted from the bore 18, the spring removed from the sections and the sections separated and taken from the valve stem, after which the valve may be inserted into its seat, the customary guide replaced in the lower end of the bore 18, its spring placed about the stem and the lock member engaged with the headed end 16 of the valve stem.

By the use of this device, the same may be entirely assembled before insertion into the bore 18 for grinding, being more convenient and affording a saving of time, and when removal is necessary, the entire valve and grinding unit may be removed for inspection without the necessity of disengaging and assembling of a furnished guide in the awkward position which it assumes.

While I have described certain construction forms which embody the principles of my invention, it is obvious that other desired changes in arrangement may be made within the spirit and the scope of the invention as defined in the appended claims.

I claim:

1. A valve stem guide and valvelifter for use in guiding valves comprising a body portion consisting of a plurality of separable sections through which the stem of the valve to be ground is guided, said body being insertable into the bore of the engine block, and a spring for engaging a portion of the body to hold the sections assembled and to lift the valve from its seat.

2. A valve stem guide and valvelifter for use in grinding valves comprising a body portion consisting of a plurality of separable sections through which the stem of the valve to be ground is guided, said body being insertable into the bore of the engine block, a spring for encircling a portion of the body and tightly fitting the same for holding the separable sections in assembled relation, and also adapted to lift the valve from its seat.

3. A valve stem guide and valvelifter for use in grinding valves comprising a sectional body having separable portions providing in assembled relation a cylindrical outer surface with a flange intermediate its ends, and an axial opening of a size to receive and guide a valve stem, the body portion below said flange being of a size to fit the bore on the engine block,

the upper portion above said flange being cylindrical substantially throughout its length and a coiled spring surrounding the upper portion of said body and tightly fitting the same for holding the sections in assembled relation and adapted to surround the valve stem and engage the valve head and resiliently lift the same from its seat.

4. In combination for use in grinding a valve seat, a one-piece valve comprising a stem having a head at one end with a finished seat, and an enlargement at its opposite end, a guide comprising a body portion consisting of a plurality of separable sections to fit about the stem of the valve and guide it in grinding, and receivable in the bore of the engine block adjacent the valve seat, and a spring encircling the upper end of said body and tightly fitting the same to hold the sections in assembled relation about said stem and lift the valve from its seat.

In testimony whereof I affix my signature.

RUDOLPH TRAHAN.
